UNITED STATES PATENT OFFICE.

CARL BRANDT, OF CEDAR FALLS, IOWA.

HEATING-FURNACE.

SPECIFICATION forming part of Letters Patent No. 658,907, dated October 2, 1900.

Application filed May 25, 1900. Serial No. 17,982. (No model.)

To all whom it may concern:

Be it known that I, CARL BRANDT, a citizen of the United States, residing at Cedar Falls, in the county of Black Hawk and State 5 of Iowa, have invented a new and useful Heating-Furnace, of which the following is a specification.

My invention is an improved heating-furnace, the object of my invention being to provide a novel form of heating-furnace which is adapted to create a downward draft directly through the fire in the fire-pot, so as to consume the smoke and effect an economy of fuel, and which is also adapted to create a direct 15 upward draft through the fire-pot to the smoke-exit at will and which is adapted for burning either hard or soft coal.

My invention consists in the peculiar construction and combination of devices herein- 20 after fully set forth, and pointed out in the claims.

In the accompanying drawings, Figure 1 is a perspective view of a furnace embodying my improvements. Fig. 2 is a horizontal sec- 25 tional view of the same on two planes, one half of said figure being a section on a plane taken through the radiator and the other half thereof being a section taken on a plane through the dome over the fire-pot. Fig. 3 is 30 a vertical central sectional view taken on the line *x x* of Fig. 2. Fig. 4 is a similar view taken on the line *y y* of Fig. 2.

From the center of the circular base-ring 1 rises the ash-pit 2, which has a horizontal ex- 35 tension 3 on one side thereof, the outer end of which is open and provided with a door 4, whereby it may be closed. The grate 5, which may be of any suitable form, is mounted and supported on a bridge-plate 6, which is trans- 40 versely disposed in the ash-pit, the ends of the said bridge-plate being supported on lugs 7 in the sides of the ash-pit.

The ash-pit is provided on its upper side with a circular opening, with which the grate 45 is coincident, and said circular opening is surrounded by an annular groove 8, which is concentric therewith and is formed in the upper side of the ash-pit, in which annular groove is seated the lower edge of the fire-pot 9, which in the form of my invention here shown is cylindrical and is provided in its upper edge with an annular groove 10, which

receives the lower edge of the dome 11. The dome is provided on its front side with a horizontal extension 12, through which fuel 55 is introduced to the fire-pot and which is provided with a door 13, whereby it may be closed, and preferably said door is provided with an opening or series of openings 14 of usual form, provided with a draft-regulator 15. From 60 the side of the dome opposite the extension 12 projects a smoke-exit flue 16, in which is a pivoted damper 17, which is adapted to open communication between said flue and the combustion-chamber or entirely close such com- 65 munication at will.

A radiator 18, which is annular in form, as shown, is supported on the extension 12 and flue 16 and communicates with the latter, as at 19, and said radiator is adapted, on the side 70 where it communicates with said flue, for the attachment of a smoke-pipe 20. A pair of spirally disposed or inclined baffles 21 are located in the radiator and divide the same into lower compartments or flues 22 and upper 75 compartments or flues 23, said baffles extending from the bottom of the radiator at points opposite the opening 19 nearly to the side of said radiator opposite said opening 19, an opening 24 being formed between the upper 80 ends of the baffles, which opening 24 establishes communication between the lower and upper flues or compartments of the radiator. An opening 25 in the side of the radiator at a point below the opening 24 permits access 85 to the interior of the radiator, whereby the lower flues therein may be cleaned, and said opening 25 is provided with a suitable cap or closure 26. Pipes 27 communicate with the lower flues or compartments of the radiator, 90 preferably at diametrically-opposite points, as at 28, and the lower ends of said pipes communicate with the interior of the ash-pit, as at 29, at points substantially on a plane with the grate.

The operation of my invention is as follows: When the damper 17 is closed in the flue 16, as shown in Fig. 4, the draft passes downward through the fire in the fire-pot, thus causing the smoke to be consumed and 100 the fire to be maintained at an intense heat. The heated air, which passes downward from the fire, passes upward through the pipes 27 into the lower flues of the radiator, from

thence upward through the opening 24 into the upper flues of the radiator, and rearward therethrough to the smoke-pipe 20, the baffles in the radiator thus causing the heated air and gases to pass twice substantially through the radiator, and hence securing the maximum heating results. When it becomes desirable or necessary from any cause to secure a direct upward draft through the fire-pot, 10 this may be readily accomplished by opening the damper 17, thereby establishing direct communication between the combustion-chamber and the smoke-pipe 20.

A draft-pipe 30 leads from an exterior point 15 above the ash-pit to an opening in the top of the dome, as shown, and serves to convey air to the combustion-chamber, which is heated therein and passes as a hot blast downward through the fire-pot hereinbefore described.

20 It will be observed by reference to the drawings that the grate 5 is placed on the bridge-plate 6 and so located that the top of the grate is in the same horizontal plane as the lower sides of the lower ends of the pipes 27, thereby 25 leaving an air-space between the lugs and ash-pit, through which the hot-air blast is drawn downward through the fire, following the space between the lugs and ash-pit toward the pipes 27 and up through said pipes into 30 the lower flues of the radiator.

It will be understood that any desired number of the pipes 27 may be used.

I do not desire to limit myself to the precise construction and arrangement of parts hereinbefore described, as modifications may be made therein without departing from the spirit of my invention, and alterations may be made in existing heating apparatus of va-

rious forms so as to apply my invention thereto.

It will be understood that in a heating apparatus in which my invention is embodied the smoke being drawn downward and caused to pass through the fire is consumed.

Having thus described my invention, I claim—

1. A furnace having a radiator communicating with the smoke-exit, flues between said radiator and the ash-pit, to create down-drafts through the combustion-chamber, a direct flue between the combustion-chamber and the smoke-exit and communicating with said radiator, a damper in said flue, and a draft-pipe leading to the top of the combustion-chamber, to admit air thereto, substantially as described.

2. A furnace having a radiator provided with inclined baffles forming upper and lower communicating flues in the radiator, pipes to establish communication between the lower radiator-flues and the ash-pit, at a point below the grate, and said upper flues of said radiator having a smoke-exit, said furnace being further provided with a direct flue to establish communication between the combustion-chamber and said upper radiator-flue, said direct flue having a damper, for the purpose set forth, substantially as described.

In testimony that I claim the foregoing as my own I have hereto affixed my signature in the presence of two witnesses.

CARL BRANDT.
